UNITED STATES PATENT OFFICE

LEWIS J. STERN, OF NEW YORK, N. Y.

ELECTRIC CLOCK

Original application filed April 18, 1924, Serial No. 707,321. Divided and this application filed December 21, 1928. Serial No. 327,662.

My invention relates to improvements in electric clocks and the main object of the invention is to provide an arrangement which is more easily assembled and disassembled for repair and replacement of parts, etc. and which is generally more efficient in construction and operation. To this end my improvements consist of various features of construction which will more clearly appear from the detail description given below taken in connection with the accompanying drawings which form a part of this specification.

This application is a divisional application from my pending application, Serial No. 707,321, filed April 18, 1924, for electric clocks.

In the drawings Fig. 1 is a perspective of a clock located in the dash of an automobile, the clock embodying my improvements in a preferred form thereof. Fig. 2 is a front elevation of the clock parts with the outer casing, dial etc. removed. Fig. 3 is an elevation of the parts shown in Fig. 2, taken at right angles thereto. Fig. 4 is a rear elevation of the parts shown in Figs. 2 and 3. Fig. 5 is a vertical section taken on the line 5—5 of Fig. 4, the surrounding casing and the parts for securing the clock to the dash-board being also shown in section therewith. Fig. 6 is a view similar to Fig. 4 with the electro-magnet windings removed. Fig. 7 is a view showing some of the parts, the section being taken on the line 7—7 of Fig. 6. Fig. 8 is a top plan view of the clock secured to the dash-board. Fig. 9 is a detail section through the axis of the main arbor of the clock showing the method of securing the clock hands thereto. Fig. 10 is a rear view of the clock movement and Fig. 11 is a side view of the same.

Referring to the drawings, 1 represents the dash-board of an automobile for use on which the clock is specially adapted, although it will be found useful in many other situations. 2 represents a cylindrical casing closed at one end by the integral plate or end 3 so that the casing is cup-shaped. Screwed into the front end of the casing so as to be easily removable therefrom is a flanged rim 4 adapt-

ed to hold the front glass 5 through which the clock face is visible.

Within the casing is a circular frame plate 6, having secured to the front thereof a flat ring 7 of the same outside diameter. Rigidly secured to the plate 6 on the other side thereof is another circular frame plate 8. The plates 6, 7, and 8 are rigidly secured together in parallel spaced relation by posts and spacing bushings 9.

The clock movement (shown separately in Figs. 10 and 11) comprises two spaced apart circular plates 10 and 11. These plates are held rigidly secured to one another by connecting posts 12 with the clock movement gears and arbors therebetween and carried thereby, the main arbor being indicated at 13, the hair spring at 14 and the slow and fast regulating lever at 14a having the usual loop 15 engaging the hair spring. On the same axis as the main arbor is a sleeve 16 which sleeve extends through the rear plate 10 and carries a ratchet wheel 17. The parts are so arranged that upon a spring tending to rotate the ratchet wheel the clock movement will be operated.

The main frame plate 6 is centrally apertured as indicated by the line 18 on Fig. 2 the aperture being sufficiently large to receive the clock movement, the rear plate 10 being small enough to pass therethrough. The edge of the aperture is rabbeted to receive the edge of the plate 11 which will not pass through the aperture and the whole clock movement is rigidly secured in place to the main frame plate 6 by screws 19 screw-threaded in the plate 6 but the heads of which overlap the edge of the plate 11 to hold the same and the whole clock movement firmly in place and rigid with the plate 6. Thus the whole clock movement unit as shown in Figs. 10 and 11 may be easily removed from the frame plate 6 by merely removing the screws 19. The rear frame plate 8 is also provided with a central circular aperture large enough to permit the ratchet wheel 17 to pass therethrough so that when the parts are in place the ratchet will be on the rear side of the plate.

The dial of the clock is shown at 20 and this is secured to the ring 7 in front of the

main frame plate 6 by bending certain projections from the periphery of the dial about the outer edge or periphery of the ring 7 as shown at 21 (see Fig. 5). Extending through the dial 20 is a sleeve 22 (see Fig. 9) having fixed on the front end thereof the hour hand 23 and on the inner end thereof a gear 24. Between the gear 24 and the dial 20 is a leaf spring 25a which tends to force the gear 24 away from the dial. When the dial is put in place the sleeve 22 is slipped over the front end of the arbor 13 with the gear 24 maintained in mesh with a gear 25 (see Fig. 3) which is rigid with a gear 26 which in turn meshes with a gear 27 secured on the main arbor 13. The end of the arbor 13 is made square or non-circular in cross-section and the minute hand 28 is provided at its axis with a corresponding aperture adapted to fit over this portion so as to be turned thereby. The minute hand 28 is held rigidly on the arbor by the head of a screw 29 which is screw-threaded into the end of the arbor 13. As the clock is operated and the arbor 13 is turned, the minute hand 28 turns with it at the same speed. The sleeve 22 is capable of turning on the arbor 13 and by means of the reducing gears 27, 26, 25 and 24 is driven one-twelfth as fast as the arbor 13 and the minute hand whereby the hour hand 23 secured on the sleeve is driven at the hourly speed. In order to more firmly hold the sleeve 22 with the hour hand, on the arbor 13, the arbor 13 has a reduced cross-section as at 30 and the sleeve 22 is pressed inwardly therat so that it is effectively prevented from slipping longitudinally on the arbor. Thus both hands are firmly held in place and can not be jarred off as would otherwise be likely when the clock is subjected to excessive jarring such as occurs in use on automobiles.

31 is a bracket attached to rear face of the circular frame plate 8 (see Figs. 4 and 6) and journaled between the end of the bracket and the plate 8 is a pivot 32 carrying an armature 33 adapted to be attracted by the polar ends 34 of electro-magnets 35. The armature 33 carries rigid therewith an arm 36 extending away from the pivot 32 at right angles to the armature. Pivotedly mounted on the end of the arm 36 is a pawl 37, normally pressed against the teeth of the ratchet 17 by a coiled tension spring 38. One end of the spring 38 is secured to a fixed bracket 39 on the plate 8 and the other end of the spring is secured to a hook 40 on the pawl 37 a short distance from the point where the pawl is pivoted to the arm 36. The spring is so positioned that it not only tends to rotate the pawl about its pivot and into engagement with the teeth of ratchet wheel 17, but also the spring 38 pulls on the arm 36 in a direction to cause the pawl to rotate the ratchet wheel 17 and operate the clock. As the ratchet

wheel so rotates the armature 33 swings away from the pole pieces 34.

Pivotedly mounted between a bracket 41 and the plate 8 is a switch lever 42 having an upturned lug 43 to which is connected one end of a coiled tension spring 44, the other end of the spring 44 being connected to a projecting arm 45 on the armature 33. The switch member 42 is provided with an arm 46 adapted to engage a post 47 struck up from the plate 8, to limit the movement of the switch member in open position. Pivoted between the bracket 48 and the plate 8 about a pivot 49 is a switch contact member 50 carrying an electrical contact at 51 suitably insulated from the member 50 but electrically connected in circuit with the magnets 35 by means of a coil of spring wire conductor 52. The member 50 has an arm 53 extending in the opposite direction from the pivot, which arm is bent over at its outer end and extends into a slot 54 in the face of the plate 8 thereby limiting the movement of the member 50 about its pivot 49 to a very slight movement determined by the play which the arm 53 has in the slot 54. The contact 51 is preferably made of silver while the switch arm 42 carries an electrical contact 55 of silver or other suitable metal. The magnets 35 are electrically connected in series with one another by conductor 56. One terminal 57 of the two magnets is connected to one side of a source of electrical energy such as a storage battery while the other terminal of the battery is grounded on the metal parts of the apparatus.

Assuming the parts to be in the position shown in Fig. 4, the spring 38 will be under tension and will pull upon the arm 36 causing the pawl 37 to engage ratchet 17 and turn the same to operate the clock. As the arm 36 moves slowly under the action of the spring 38, being retarded by the escapement mechanism of the clock movement, the armature 33 simultaneously gradually moves away from the pole pieces 34 and carries with it the end of spring 44 which is attached to the lug 45. When the line between the two ends of the spring 44 is swung over to the other side of the pivoting point on bracket 41, the spring 44 suddenly swings or snaps the switch member 42 about its pivoting point causing the contact 55 to swing into electrical contact engagement with the contact 51 and make contact therewith (as shown in Fig. 6) with more or less of a sliding contact so as to keep the engaging faces of the contacts clean. To facilitate this the contact member 51 is carried by the pivotedly mounted arm 50 and resiliently held toward the contact 55 by the weak spring 52 so that when the switch member 42 is swung into engagement with the contact 51 it causes a slight movement of the member 50 about its pivot thereby permitting the contact faces to slide or rub over one an-

other in order to insure good electrical contact.

When the contact 55 which is electrically grounded to the metal parts of the apparatus 5 engages the contact 51, the circuit is completed through the magnets which causes the armature 33 to be attracted and the arm 36 again moved to the position shown in Fig. 4 which again places the main spring 38 under its original tension. During this movement the pawl 37 slips over one or more teeth of the ratchet 17 but at once continues to operate the same as before, merely engaging the ratchet in a different place. After 10 the armature has been attracted a certain distance toward the pole pieces 34 but before actually coming against the pole piece, the line between the two ends of the spring 44 passes to the other side of the axis about 15 which the switch member 42 is pivoted, whereupon the spring 44 snaps the switch 42 open and causes the switch contact 55 to be quickly withdrawn from the contact 51. The resulting backward opening movement of 20 the switch is limited by the arm 46 engaging the bracket post 47 which also serves as a back stop for the armature 33 which is drawn thereto by the main spring 38 when the magnets are disconnected from the source of electrical energy. The parts may be so adjusted 25 that the switch member will automatically close the circuit through the magnets about once every minute but it will be seen that as soon as the circuit is closed, the armature is 30 immediately attracted and places the spring 38 substantially under its initial tension and immediately opens the switch, so that the spring will again perform its function of supplying the necessary force to operate the 35 clock or time piece. The armature 33 at its outer end carries an arm 58 extending toward the frame plate 8. This arm is so positioned, that, should the spring 44 fail to open the switch when the armature is attracted by 40 the electro-magnet, the arm 58 will engage the switch lever 42 and kick the switch open.

The switch member thus intermittently controls the energization and deenergization 45 of the electro-magnets and the spring 44 connected at one end to the switch member at a point on one side of its pivot and at the other end to a point on the other side of the pivot and to the armature, is adapted to throw the switch in each direction in response to the 50 movement of the armature in each direction, and also to hold the switch at the end of its travel in each direction until the armature has moved a substantial distance from the 55 end of its travel.

In order to secure the parts firmly in the 60 casing 2, 3, posts 60 are rigidly secured to the frame 6 and extend rearwardly therefrom. The plate 8 is cut away at the edges to accommodate these posts. The posts 60 are provided with end portions 61 reduced in

cross-section and which are screw-threaded. These screw-threaded end portions extend through holes in the back 3 of the casing and nuts 62 are applied thereto and screwed up thereon to hold all the parts rigidly in the 70 casing. It will be seen that back 3 acts as a rear frame plate rigidly connected to the front frame plate 6 by the posts 60 and the electro-magnetic means with its associated parts for operating the clock movement are 75 carried between these plates and by the front plate 6 independently of the clock movement unit which is readily removable from the frame plates by merely removing the screws 80 19 after the glass 5 is removed by unscrewing the rim 4.

In order to operate the slow and fast regulating lever 14a from the back of the clock, a spindle 64 is provided. This spindle is journaled in one of the posts 65 which support and rigidly connect the core 66 of the electro-magnet upon the frame plate 8. The spindle 64 extends through the back 3 and has a knob 67 rigidly screwed thereon for the purpose of conveniently turning the same 90 from the back of the clock. At its opposite end the spindle 64 has secured thereto a forked member 68, the forked part of which is arranged eccentric to the axis of the spindle 64 and engages the slow and fast regulating lever arm 14a (see Fig. 7) so that upon turning the spindle 64 from the back of the clock, the forked portion may be oscillated back and forth to similarly move and adjust the slow and fast regulating lever arm 14a of 100 the clock movement. It will be noted, however, that the spindle and fork are not otherwise connected to the clock movement unit but are carried by the frame plates, and the clock movement unit may be removed without 105 in any way disconnecting the spindle and its fork from their support or from one another. When the clock movement unit is removed from the frame plates 7 and 8 it simply slips out of the fork. The lever 14a has a forwardly projecting arm 69 which extends into a slot in the dial 20 so as to be visible from the front of the clock, and thus indicate on the face of the clock the extent to which adjustment has been made. 115

In order to provide means for adjusting the setting of the hands from the back of the clock, there is provided another similar spindle 70 journaled in a bushing 71 secured rigidly in the frame plate 8. The spindle 70 is capable of sliding axially in the bushing and its rear end projects through a hole in the back 3 and has rigidly screwed thereon a knob 73 so that the spindle 70 is readily turned as 120 well as moved axially from the back of the clock. At its front end the spindle 70 has rigidly secured thereto a small pinion 74. Surrounding the spindle 70 between the pinion 74 and the bushing 71 is a coiled compression spring 75 which normally forces the 125 130

spindle 70 toward the front until the pinion 74 is stopped by and lies against the back side of the dial 20. 76 represents a layer pinion journaled on the front face of the plate 11 of the clock movement unit and meshes with the reducing gear 26 thereon. To set the hands of the clock from the back the operator merely grasps the knob 73 and pulls the spindle 70 rearwardly until the pinion 74 comes in the same plane and meshes with the pinion 76 and then turns the knob and spindle thereby turning the pinions and gears 74, 76, 26, 25, 24 and the hand 23 and gear 27 and main arbor 13 and hand 28 carried thereby. Upon releasing the knob 73 the spring 75 forces the pinion 74 back against the back of the dial 20 and out of engagement with the pinion 76. It will be noted that the spindle 70, like the spindle 64, is journaled in parts carried by the frame 8 and is located at the periphery of the clock movement unit so that it passes along one side of the same and not therethrough and the plates 10 and 11 of the clock movement unit are cut away at 77, whereby the clock movement unit may be removed from the rest of the parts shown in Figs. 2 and 3 without disturbing the spindle 70 or removing the pinion 74 therefrom.

In securing this clock on the dashboard the clock, assembled in the casing, is slipped into the clock hole in the dash until the rim 4 comes up against the front of the dash. The back 3 of the casing has two diametrically opposite screw-threaded posts 78 secured rigidly thereto and extending rearwardly therefrom. A bracket 79 having two inwardly extending legs 80, is provided with two holes in its back portion, corresponding to the posts 78, and this is slipped on with the posts 78 extending through these holes, until the pointed ends of the legs 80, on diametrically opposite sides of the clock, engage the back of the dashboard. Nuts 81 are then screwed up on the posts 78 whereupon the whole clock is held rigidly on the dash. The back 3 is also provided with a hole through which an electrical conductor is inserted to connect the electro-magnet with the storage battery or other source of electric energy.

While I have described my improvements in great detail and with respect to a preferred form thereof, I do not desire to be limited to such details or forms since many changes may be made and the improvements embodied in widely different forms. Hence I desire to cover all forms coming within the language or scope of any one or more of the appended claims.

What I claim as new and desire to secure by Letters Patent, is:

1. In an electric clock of the type wherein a clock movement unit is operated by an armature controlled by an electromagnet, a member pivotally mounted adjacent to said armature adapted to open and close the cir-

cuit through the electromagnet, a spring having one end connected to the armature at a point located on one side of the pivot of said member and the other end of said spring connected to a point of the said member located 70 on the opposite side of said pivot, whereby the movement of the armature causes the member to move to its open and closed circuit positions, and means on the armature adapted to positively move the member to its open 75 circuit position should said spring fail to so move it.

2. In an electric clock of the type wherein a clock movement unit is operated by an armature controlled by an electromagnet, a member pivotally mounted adjacent to said armature adapted to open and close the circuit through the electromagnet, resilient means having a part connected to the armature at a point located on one side of the pivot 80 of said member and another part of said resilient means connected to a point of said member located on the opposite side of its said pivot, whereby the movement of the armature causes the member to move to its open and closed circuit positions, associated with means on the armature adapted to positively move the said member should said resilient means fail to so move it.
